George J. Kupchik, Brooklyn Village, Ohio

Application May 22, 1951, Serial No. 15,281

Term of patent 14 years

(Cl. D80—8)

To all whom it may concern:

Be it known that I, George J. Kupchik, a citizen of the United States, residing at 6308 Archmere Ave., Brooklyn Village, in the county of Cuyahoga and State of Ohio, have invented a new, original, and ornamental Design for a Combination Bootee Drier and Coat Hanger, of which the following is a specification, reference being had to the accompanying drawing, forming part thereof.

Fig. 1 is an elevational view of a combination bootee drier and coat hanger, showing my new design.

Fig. 2 is an end elevation of the same.

Fig. 3 is a top elevation of the same, and,

Fig. 4 is a transverse section of the same taken on the line 4—4 of Fig. 1.

I claim:

The ornamental design for a combination bootee drier and coat hanger, as shown.

GEORGE J. KUPCHIK.
